UNITED STATES PATENT OFFICE.

EUGENE R. CARICHOFF, OF EAST ORANGE, NEW JERSEY, ASSIGNOR TO SPRAGUE ELECTRIC COMPANY, A CORPORATION OF NEW JERSEY.

SWITCH FOR ELECTRICAL APPARATUS.

SPECIFICATION forming part of Letters Patent No. 733,146, dated July 7, 1903.

Application filed August 1, 1901. Serial No. 70,518. (No model.)

To all whom it may concern:

Be it known that I, EUGENE R. CARICHOFF, a citizen of the United States of America, and a resident of East Orange, in the county of 5 Essex and State of New Jersey, have invented certain new and useful Improvements in Switches for Electrical Apparatus, of which the following is a specification.

The present invention relates to switches for electrical apparatus, the object of the same being to improve the general construction and render the same fireproof. Heretofore the methods of protecting apparatus, such as controllers and reversers, for the 15 switching of heavy currents for car use have not been of such a nature as to afford adequate safety where compact design was used. This invention meets the requirement.

The invention consists of certain features 20 of construction and combinations of parts to be hereinafter described and then claimed.

In the accompanying drawings, Figure 1 is a longitudinal sectional front view showing the improved construction of controller, the 25 section being on the line *x* *x* of Fig. 3. Fig. 2 is a plan view of the device with the cover removed; and Fig. 3 is a transverse section on line *y* *y*, Figs. 1 and 2.

The casing *A* of the controller has a slate 30 back *a*, through which are passed a number of studs *B*, the inner ends of which are formed with enlargements *b*, that abut against the inner wall of the slate back and form the bases for the spring contact fingers or brushes

35 *C*. The outer projecting ends of the studs are screw-threaded to receive locking-nuts *d*', that secure the terminals for the various circuits and which, as the connection is made outside the casing, remove all possibility of 40 arcs communicating to car-wiring. This disposition of studs also secures vertical insulation.

The shaft of the cylinder *E* is journaled, as usual, in the casing and carries the contacts *e*, arranged in well-known manner to 45 make contact with the fingers *C*, all surfaces of the controller-cylinder except the actual working contacts being covered with insulation. The inner surfaces of the casing are 50 well covered with sheet insulation *a'*, while the casing is transversely partitioned off by

insulation-plates *F* *F'* *F*², which provide compartments to isolate the contacts, plate *F'*, however, not entirely closing the spaces on each side from each other, so that air may 55 pass from one space to the other. Middle partition *F'* rests upon a horizontal plate or air-deflector *F*³, and this in turn rests upon a low vertical plate or air-deflector *F*⁴, located on the bottom of the casing between 60 openings *g* *g'* therein, from which extend downwardly-extending oppositely-presented elbow-funnels *g* *g'*. In this way horizontal air chutes or channels *g*² *g*³ are formed, which in connection with the funnels *g* *g'* no matter in which direction the car may be moving 65 act to cause a circuitous current of air, and thereby thoroughly ventilate the interior of the casing and keep the parts as cool as possible. Blow-out coil *H* is isolated and separated from the working contacts by the partition *F*².

Cover *I* of the casing is hinged at its rear edge to the back of the same and is formed at its edges with a depending flange *i*, which 75 when the cover is closed embeds in packing *j*, located in the groove of a gutter *j'*, extending along the outer upper portion of the casing. Attached to the under side of the cover are the heat-conducting separations *K* for 80 chilling the arc and made of reconstructed granite. By this construction the separations *K* are moved out of the casing simultaneously with raising of the cover.

What I claim as new, and desire to secure 85 by Letters Patent, is—

1. In a switch for electrical apparatus, the casing provided with partitions forming compartments to isolate the contacts, substantially as described.

2. In a switch for electrical apparatus, a casing having a side of insulating material, and studs for the terminals, said studs extending through said side and having at the inner ends abutting enlargements or shoulders for the contact-fingers, the other ends projecting for attachment of the terminals; substantially as described.

3. In a switch for electrical apparatus, the casing and a hinged cover on which are 90 mounted the heat-conducting separations for chilling the arc, substantially as described.

4. In a switch for electrical apparatus, the casing provided with two ventilating-openings, and means for causing, through one or the other of said openings, according to the direction of movement of the vehicle a continuous circulation of air in the casing, substantially as described.

5. In a switch for electrical apparatus, the casing provided with two ventilating-open-

ings, a deflector arranged above the openings, and a deflector between the openings, substantially as described.

Signed at New York city, New York, this 31st day of July, 1901.

EUGENE R. CARICHOFF.
